Des. 209,385
Patented Nov. 28, 1967

209,385

SHIRT CUFF

Robert V. Kay, 1635 N. 44th Ave.,
Stone Park, Ill. 60165

Design application Apr. 1, 1965, Ser. No. 84,682, now Patent No. 207,090, dated Mar. 7, 1967, which is a division of application Ser. No. 82,559, Apr. 12, 1964. Divided and this application Oct. 10, 1966, Ser. No. 5,011

Term of patent 3½ years

(Cl. D2—379)

Fig. 1.

Fig. 2.

Fig. 3.

Fig. 4.

FIG. 1 is a perspective view of a shirt cuff showing my new design;

FIG. 2 is a side perspective view of the design shown in FIG. 1, the side opposite that shown being a mirror image thereof;

FIG. 3 is a perspective view showing a modification of my design; and

FIG. 4 is a side perspective view of the design shown in FIG. 3.

The band that is positioned inside the cuff fold is stippled to represent a color contrast.

This application is a division of my application Ser. No. D. 84,682, filed Apr. 1, 1965 and now Patent No. D. 207,090 which is a division of my application Ser. No. D. 82,559, filed Apr. 12, 1964 and now abandoned.

I claim:

The ornamental design for a shirt cuff, substantially as shown and described.
